UNITED STATES PATENT OFFICE

129,508

DESIGN FOR A COMBINATION COLLAPSIBLE TUBE AND MASSAGE DEVICE

Joseph N. Landau, New York, N. Y.

Application June 22, 1940, Serial No. 93,184

Term of patent 14 years

To all whom it may concern:

Be it known that I, Joseph N. Landau, a citizen of the United States, residing at New York, in the county of the Bronx and State of New York, have invented a new, original, and ornamental Design for a Combination Collapsible Tube and Massage Device, of which the following is a specification, reference being had to the accompanying drawing, forming a part thereof, in which:

Fig. 1 is a side view in elevation of the combination collapsible tube and massage device embodying my new design;

Fig. 2 is a side view in elevation of the device shown in Fig. 1 with the cap removed; and

Fig. 3 is a fragmentary front view of the device shown in Fig. 2, with a portion of the bottom broken away for convenience of illustration.

I claim:

The ornamental design for a combination collapsible tube and massage device substantially as shown.

JOSEPH N. LANDAU.
